UNITED STATES PATENT OFFICE.

GEORGE O. RICHARDS AND MARTIN S. MILLER, OF CLEVELAND, OHIO.

FURNACE.

No. 893,196.

Specification of Letters Patent.

Patented July 14, 1908.

Application filed January 14, 1908. Serial No. 410,815.

To all whom it may concern:

Be it known that we, GEORGE O. RICHARDS and MARTIN S. MILLER, citizens of the United States, residing at Cleveland, in the county of Cuyahoga and State of Ohio, have invented certain new and useful Improvements in Furnaces, of which the following is a specification.

This invention relates to hot air furnaces, and has for its object to provide improved means for heating the air which is supplied by the furnace, said means embodying a cylinder or air chamber located in the jacket above the fire pot and connected to the surrounding space in the jacket by means of a large number of short horizontal flues or pipes around which the products of combustion circulate before they pass to the smoke flue.

Improved means are also provided for controlling the amount of air caused to pass through said chamber.

The invention is illustrated in the accompanying drawings, in which

Figure 1 is a side elevation, part of the outer jacket being broken away. Fig. 2 is a vertical section. Fig. 3 is a horizontal section on the line 3—3 of Fig. 1.

Referring specifically to the drawings, 1 indicates the outer jacket conveniently formed of sheet metal or the like and standing upon a base 15. It is provided at the bottom with an air inlet 9. This jacket has a top 23, and service pipes 13 by which the hot air is delivered as desired.

The fire pot is indicated at 5, with a fuel door 6, an ash pit, as at 8, and a grate 16 with operating rod 27.

Above the fire pot is a cylinder or drum 3 and within this, and spaced therefrom, is another cylinder or drum 14. These cylinders are connected by a considerable number of short horizontal pipes 4 which extend across the space between the drums, and allow the passage of air from the space 19, within the jacket, to the drum 14. Said drum 14 is closed at the bottom and is located directly above the center of the fire pot, in position to receive the greatest heat thereof. The space between the drums 3 and 14 is closed at the top, as indicated by 20, except for the flue pipe 17 leading to a chimney. The space between the drum 3 and the jacket 1 is also

closed or provided at the top with an annular plate 12 which is provided with a series of openings 21 and mounted upon top of this plate is another movable annular plate 11 which is provided with similar openings and which may be turned by means of a handle 10 projecting through a slot 2 in the side of the jacket. By turning the valve plate 11 the openings are controlled. When they are closed, all the heated air necessarily passes from the space 19 through the pipes 4 and the central chamber 14. This heats the air to the highest degree possible. When more moderate temperature is desired the plate may be turned to open the valve more or less, and part of the air at least will flow directly through the openings 21 to the top of the jacket and thence to the service pipes.

The arrangement shown causes the heated air, when conducted through the central heating chamber, to absorb heat to a high degree, from the adjacent tubes and the walls of the chamber, which, as stated, are exposed to the products of combustion flowing thereover. The drums and the connecting pipes are preferably constructed of sheet metal and can be set in place upon the fire pot.

Although illustrated in connection with a coal burner, the apparatus can without invention be modified to receive its heat from a gas burner placed within the fire pot.

We claim:

In a furnace, the combination of a fire pot and an outer jacket, inner and outer spaced drums located above the fire pot and within the jacket and below the top thereof, forming a hot air chamber in the upper part of the jacket, with an air space between the outer drum and the sides of the jacket, the inner drum opening at the top into the said chamber, and a plurality of horizontal pipes extending across the space between the drums and connecting the chamber within the inner drum with the said air space between the outer drum and the jacket.

In testimony whereof we affix our signatures, in presence of two witnesses.

GEORGE O. RICHARDS.
MARTIN S. MILLER.
